UNITED STATES PATENT OFFICE.

JOHN S. UNGER, OF DUQUESNE, PENNSYLVANIA.

METHOD OF TREATING SOLIDS OF REVOLUTION.

1,071,012.

Specification of Letters Patent.

Patented Aug. 19, 1913.

Application filed November 19, 1912. Serial No. 732,279.

To all whom it may concern:

Be it known that I, JOHN S. UNGER, a citizen of the United States, residing at Duquesne, in the county of Allegheny and State of Pennsylvania, have invented a new and useful Method of Treating Solids of Revolution, of which the following is a specification.

My invention has relation to the treatment 10 of car wheels and similar solids of revolution such as gears, brake wheels, double flanged truck wheels, crushing rolls whereby the tread and flange portion or periphery of such articles is hardened and tempered, and 15 one object of my invention is to provide a novel method of hardening and tempering such car wheels and similar solids of revolution by the use of which the structure of the steel in the rim or periphery of the articles is modified, a fine crystalline structure 20 is obtained and the rim portions are hardened or tempered.

A further object of the invention is to provide a novel method of treating such solids 25 of revolution whereby tempering or hardening of the article is restricted to the desired portions thereof.

A still further object of my invention is to provide a novel method of treating car 30 wheels and similar solids of revolution whereby excessive chilling or hardening of their flange portions thereof is avoided and prevented.

It has been proposed heretofore to spray 35 the tread or periphery of heated car wheels and like solids of revolution by means of a perforated pipe through which the fluid used in the treatment of the articles is supplied and it has also been proposed to immerse the articles in water or other tempering liquid. A still further method of hardening such articles used heretofore has been to apply a shield or cover to such portions of the article as are to remain untreated and 45 then apply water, oil or other cooling medium to the unprotected portions to harden and temper such portions of the wheel. With such methods it has been found difficult if not impossible to treat the desired 50 portions of the articles without also hardening or tempering other portions thereof.

Referring to the accompanying drawing forming part of this specification the figure is a sectional side elevation and shows one 55 form of apparatus adapted for use in carry-

ing out my improved method of treating car wheels, and similar solids of revolution.

In the drawing 2 designates a tank or trough, having a fluid inlet 3 and fluid overflow outlet 4. The overflow outlet 4 is made 60' so as to be adjustable to regulate the height or level at which the body of fluid is maintained within the trough 2 and is arranged to draw off the fluid from the upper surface thereof where the fluid will be heated to the 65 greatest extent.

Secured on the sides of the trough are bearings 5, 5 for the mandrel or arbor 6, which is constructed to enter the axle-eye of the wheels A which are removably secured 70 thereon during the wheel treating operations. By making the arbor 6 slightly tapering on the wheel seating portion thereof, the wheels will be held on the arbor by friction so as to cause the wheels to revolve when 75 the arbor is caused to rotate by the motor or other prime mover. The bearings 5 are constructed to permit of the ready removal of the arbor 6 to facilitate positioning and removing the wheel in the trough and the 80 collars 10-10 by engagement with the opposite sides of one of the bearings 5 prevent lengthwise movement of the spindle or arbor. The arbor 6 is detachably connected by a sleeve coupling 7 to the armature shaft 85 8 of a variable speed motor 9, or to a driving shaft or other prime mover.

A supply consisting of a number of arbors of different diameters will permit articles having an axial opening therein in which 90 the diameter of the axial opening varies being treated, the overflow outlet 4 being adjusted to maintain the fluid in the tank 2 at the required level, enabling articles of larger or smaller sizes being treated.

In carrying out the steps of my improved method the wheel or other solid of revolution is placed on the arbor 6, preferably after being heated to the necessary temperature. The arbor is then positioned in its 100 bearings 5 and connected by the coupling 7 to the motor 9 or other driving mechanism, and is then caused to rotate above the trough 2 with the periphery or tread of the article being treated extending below the level of 105 the water, oil or other liquid within the trough 2 for the desired distance.

When treating articles having relatively thin portions such as, for example, the flange portion of car wheels or the teeth of a gear 110

wheel, such portions will be insulated or protected from too rapid chilling of the protected portions in the cooling operation by covering the desired portion of the articles 5 with asbestos or by coating with a slurry of clay and water, or lime and water, or a mixture of clay, lime and water.

The overflow outlet 4 which is arranged to be adjustable to vary the height at which 10 the fluid is maintained within the trough 2 is first adjusted to suit the particular diameter of the article being treated so that a solid of revolution of a given diameter will be immersed the desired distance within the 15 liquid. The article is then rotated, usually at a comparatively slow speed, with the lower portion of the rim thereof extending into the fluid in the tank 2 for a sufficient time interval to cool the rim or tread portions thereof, the portions of the article extending into the fluid in the tank being thereby tempered or hardened, and in treating articles in this manner the structure of the metal in the periphery of the article or, 20 in the case of car wheels, the flange and tread forming the periphery of the wheel is changed and the desired finely crystalline 25 structure obtained.

In revolving or rotating the articles during 30 the cooling operations care is taken to not rotate the articles at a speed high enough to cause the fluid to be thrown on the other portions thereof by centrifugal force and in this way contact of the cooling medium 35 with the web portion of the wheel is avoided and prevented.

The advantages of my invention will be apparent to those skilled in the art. By rotating the articles about a horizontal axis 40 with the article positioned to immerse the desired portion of the rim portion thereof within the trough, the rim of the article is alternately exposed to the cooling medium and to the atmosphere for any desired 45 length of time.

Modifications in the construction and ar-

rangement of the apparatus may be made, and apparatus other than that shown may be applicable for use in carrying out my improved method. The bearings for the spindle or mandrel may be adjustable relative to the fluid in the trough instead of varying the level of the fluid within the trough. Means other than the spindle and spindle driving mechanism shown may be employed 55 in rotating the wheel within the scope of the appended claims, and the term "article" as used in the specification is intended to cover all solids of revolution whether provided with a flanged periphery, as in a car 60 wheel, or not.

I claim:—

1. The herein described method of treating solids of revolution which consists in covering portions of the periphery of said 65 article with an insulating coating, heating the article, then rotating the article above a tank containing a cooling medium and causing the rim of the article to project below the level of the cooling medium to expose given rim portions thereof alternately to contact with the atmosphere and with the cooling medium and thereby harden and temper the rim of said article.

2. The herein described method of tempering 75 solids of revolution which consists in rotating a heated solid of revolution about a horizontal axis, with the periphery of the article below its axial center immersed in a cooling medium to the desired depth, 80 continuing such rotation until the tempering of the rim thereof is complete, and covering portions of the periphery of said article with slurry to form a protective coating thereon before starting to rotate the article 85 being treated.

In testimony whereof, I have hereunto set my hand.

JOHN S. UNGER.
